(57) **CLAIM**

The ornamental design for a segmented light fixture with ceiling mount, as shown and described.

DESCRIPTION

FIG. 1 is a perspective view, from the bottom, of a first embodiment of a segmented light fixture with ceiling mount in accordance with the new design;

FIG. 2 is a front view thereof, with the rear view being a mirror image;

FIG. 3 is a left side view thereof, with the right side being a mirror image;

FIG. 4 top view thereof;

FIG. 5 is a bottom thereof; and

FIGS. 6-9 are front views thereof, with each view showing an alternate position of the article.

FIG. 10 is a perspective view, from the bottom, of a second embodiment of a segmented light fixture with ceiling mount in accordance with the new design;

FIG. 11 is a left side view thereof, with the right side being a mirror image;

FIG. 12 is a front view thereof, with the rear view being a mirror image;

FIG. 13 is a top view thereof; and

FIG. 14 is a bottom view thereof.

FIG. 15 is a perspective view, from the bottom, of the ceiling mount of the segmented light fixture in Embodiment 1 in accordance with the new design;

FIG. 16 is a perspective view thereof, from the top;

FIG. 17 is a perspective view thereof, from the bottom;

FIG. 18 is a front view thereof, with the rear view being a mirror image;

FIG. 19 is a top view thereof;

FIG. 20 is a bottom view thereof; and

FIG. 21 is a left side view thereof, with the right side being a mirror image.

FIG. 22 is a perspective view, from the bottom, of another embodiment of the ceiling mount of the segmented light fixture in accordance with the new design;

(Continued)

FIG. 23 is a perspective view thereof, from the top;
 FIG. 24 is a perspective view thereof, from the bottom;
 FIG. 25 is a front view thereof, with the rear view being a mirror image;
 FIG. 26 is a top view thereof;
 FIG. 27 is a bottom view thereof; and,
 FIG. 28 is a left side view thereof, with the right side being a mirror image.
 The broken lines shown in the drawings are for the purpose of illustrating portions of the segmented light fixture with ceiling mount that form no part of the claimed design.
